UNITED STATES PATENT OFFICE.

MARTIN A. O'CONNOR, OF BUFFALO, NEW YORK, ASSIGNOR TO W. H. MINER COMPANY, OF CHICAGO, ILLINOIS, A CORPORATION OF ILLINOIS.

FRICITION DRAFT-RIGGING FOR RAILWAY-CARS.

1,093,879.

Specification of Letters Patent.

Patented Apr. 21, 1914.

Application filed June 26, 1909. Serial No. 504,500.

To all whom it may concern:

Be it known that I, MARTIN A. O'CONNOR, a citizen of the United States, residing in Buffalo, in the county of Erie and State of New York, have invented a new and useful Improvement in Friction Draft-Rigging for Railway-Cars, of which the following is a specification.

My invention relates to friction draft rigging for railway cars.

The object of my invention is to provide a friction draft rigging of a strong, simple, efficient and durable construction, having at the same time both a high cushioning capacity and a perfect, certain and reliable release action, free from all liability or danger of the friction devices sticking or failing to properly release, and which will be composed of few parts of simple form and capable of being manufactured at small cost.

To practically accomplish this object or result and herein my invention consists, I combine with the draw-bar, draft yoke, draft lugs or stop members and front and rear followers, a longitudinally movable friction case or shell, preferably of cylindrical form, arranged between the followers and having at one end a plurality of internal friction faces, each slightly slanting or inclined to the axis of the friction case or cylinder, the angle being very acute and preferably such as to give a slant of about three sixteenths of an inch in seven inches, and each of these slightly slanting or longitudinally inclined internal friction faces being preferably of cylindric form or a segment of a cylinder; a plurality of coöperating longitudinally sliding segmental friction shoes, each having an external cylindric friction face fitting and corresponding to one of the internal friction faces of the case or cylinder, the friction shoes being adapted to move inwardly or radially toward each other to a slight extent as the friction shoes travel or frictionally slide along the slightly slanting internal friction faces of the case or cylinder as the draw-bar moves back and forth, each of the friction shoes having at its outer end a blunt wedge face, preferably about fifty-five degrees; a wedge having a plurality of corresponding blunt wedge faces, one for each of the friction shoes and interposed between the friction case or cylinder and one of the followers; and a spring with- 55 in the friction case or cylinder interposed

between the opposite end thereof and the inner end of the friction shoes so that the spring reacts at one end against the friction case or cylinder, and at its opposite end against the friction shoes. By this coöperative combination of parts, I find and have demonstrated by my experiments that with a spring of say, twenty-five thousand pounds capacity my friction draft rigging will have an exceedingly high cushioning capacity approximating four hundred thousand pounds resistance, while at the same time the friction devices are entirely free from all tendency or danger to stick and the draft rigging operates with great perfection, certainty and reliability in its release action. In operation, the blunt faced wedge engaging the blunt wedge faces of the friction shoes acts initially or primarily to force or hold the friction shoes radially outward from each other and against the surrounding friction case or shell, while at the same time, as the friction shoes travel longitudinally inward along the slightly slanting friction faces of said case or shell, the friction shoes are necessarily simultaneously crowded inward by the acute angle inclines of the friction faces of the friction shell, thus creating a very high friction resistance to the inward longitudinal movement of the friction shoes along the friction shell in compressing the spring which is interposed between the friction shoes and friction shell. And in releasing, as the wedge is an extremely blunt faced one, the instant the blow or pressure of the draw-bar is relieved, the blunt faced wedge leaves the friction shoes perfectly free to slightly collapse inward or toward each other, and thus relieve their extremely tight frictional contact or engagement of their external longitudinal friction faces with the internal longitudinal friction faces of the friction shell, thereby enabling the friction devices to perfectly, properly, reliably and certainly release without danger of sticking or failure to release.

The release action of my draft rigging is further facilitated as the friction shoes move outward and the release movement proceeds, by the circumstance that the pressure of the shoes against the wedge at their interengaging wedge faces tends to retard the outward radial movement of the shoes against the slightly slanting and divergent friction faces of the friction shell. And in the cushioning or

ioning action of my draft rigging, when the shoes are being forced inward and the spring compressed, the interengaging blunt wedging faces of the friction shoes and wedge causes the wedge to act as a safety or relieving device against too high frictional resistance being developed between the external friction faces of the shoes and the internal friction faces of the shell by permitting the friction 10 shoes to move radially inward or toward each other and thus relieve them from too extreme outward pressure against the friction shell which might otherwise burst the same because of the extremely acute longitudinal slant of the internal friction faces of the shell. By properly coöperatively adjusting the angle of the interengaging blunt wedge faces of the wedge and friction shoes, the governing action of the wedge against 20 development of too extreme pressure and frictional resistance between the friction shoes and shell may be increased or diminished as desired or required to prevent all 25 improper or dangerous development of friction and outward pressure of the friction shoes against the friction shell. A washer or wear plate is preferably interposed between the inner end of the series of segmental friction shoes and the adjacent end of the 30 spring, and a connecting bolt is preferably provided between the wedge and the opposite end or head of the friction case or cylinder, the same serving to hold all the parts assembled within the friction shell and the 35 spring under an initial tension or compression. The inner ends of the friction shoes which engage the wear plate or washer are preferably provided with beveled faces at their outer portions so that the bearing contact 40 of the washer or wear plate against the friction shoes is concentrated near the center or axis of the cylinder, as this construction tends, during the release movement or the final part thereof to more certainly 45 store the outer ends of the friction shoes into snug engagement with the internal friction faces of the friction shell. If the chief releasing pressure of the spring against the friction shoes were concentrated at the periphery 50 thereof, it would tend to tilt the outer ends of the friction shoes inward or toward each other instead of outward or away from each other as is done by the concentration of the releasing pressure against the inner corners of the friction shoes.

My invention further consists in the novel construction of parts and devices and in the novel combinations of parts and devices herein shown and described.

60 In the accompanying drawing forming a part of this specification, Figure 1 is a side elevation, partly in central vertical longitudinal section of a friction draft rigging embodying my invention. Fig. 2 is a plan view partly in horizontal section. Fig. 3 is

a vertical cross section on line 3—3 of Fig. 1. Fig. 4 is a detail cross section of the friction case or cylinder on line 4—4 of Fig. 1. Fig. 5 is a detail front end view of the friction case, shoes and wedge. Fig. 6 is a detail rear 70 end view of the friction shell. Fig. 7 is a detail view of one of the friction shoes. Fig. 8 is a detail view of the blunt faced wedge. Fig. 9 is a detail view of the removable head, cap or end piece of the friction shell and 75 Fig. 10 is a detail view of the removable spring seat which fits inside the friction shell at the rear end thereof.

In the drawing, A represents the center sills or other frame members of a car to 80 which my draft rigging is illustrated as being applied, A¹ the front or end sill, A² the carry-iron, B the draw-bar of the coupler, B¹ the draft yoke, C C¹ front and rear followers, D draft lug members or stop castings 85 secured to the draft sills for the followers to abut against, the front draft lug or stop d, rear draft lug or stop d¹ and limiting stops d² d³ the latter two being preferably both formed in one integral member, instead of in 90 separate pieces, and E E¹ the cushioning springs. All these parts are or may be of any suitable or well known construction.

F is the longitudinal movable friction case or shell, preferably of a generally cylindrical form, and arranged between the front and rear followers. The friction case F is provided with a plurality, preferably three longitudinally extending internal friction faces f, each inclined at a very acute angle 95 to the axis of the case or cylinder F, the slant being preferably about three sixteenths of an inch radially in seven inches longitudinally of the cylinder. Each of these friction faces f is preferably cylindric in form, 100 or a segment of a true cylinder, all the segments having a common center f¹ at the inner ends of the friction faces, and each of the friction faces being struck at their outer ends about three separate centers f², each 105 about three sixteenths of an inch from the axis or center f¹ of the cylinder, thus giving a slight slant to the longitudinal friction faces from their outer ends toward their inner ends.

115 The dotted line g⁴ in Fig. 5, representing the inner end of the friction faces, g g g, where their centers coincide or approach nearer together, indicates the extent of longitudinal slant of the friction faces by the 120 divergence of said dotted line from the adjacent full line to which the letter g is applied and which shows the curve of the friction faces at their outer or larger ends.

125 The longitudinally movable segmental friction shoes G are preferably three in number, and each has an external cylindric friction face g fitting and corresponding to the internal friction face f of the friction shell F along which it is adapted to longi- 130

tudinally slide or travel as the draw-bar moves back and forth, the longitudinal travel of the friction shoes in the friction shell corresponding in amount substantially to that of the draw-bar and draft yoke in each cushioning and releasing movement of the draft rigging.

The springs E E¹ are interposed between the friction shoes and the friction shell, the same re-acting at one end against the friction shell F and at the opposite end against the friction shoes, a washer or bearing plate G¹ being preferably placed between the inner end of the several friction shoes and the adjacent end of the springs to take the wear and give an even bearing. Each of the friction shoes is provided with beveled faces at the outer or peripheral portion of its inner end as indicated at g¹ so that this beveled portion will not engage the bearing plate and so that the engagement of the bearing plate against the friction shoes will be concentrated at the central, flat right-angle face g² at the central portion of the inner end of each shoe adjacent to the axis of the cylinder.

Each of the friction shoes G is provided at its outer end with a blunt wedge face g³, the angle thereof being preferably about fifty-five degrees more or less, such as to prevent any possibility of any sticking action between the same and the blunt faced wedge H which is interposed between the friction shoes G and the adjacent follower.

The wedge H is a pyramidal one, or has a series of blunt wedge faces h, one for each of the series of segmental friction shoes G.

The friction case or cylinder F is preferably furnished with a separate piece head, cap or end-piece F¹ having a countersink or recess f¹ to receive the nut K¹ of the connecting rod K, and with a spring seat plate F² which is interposed between the rear end of the springs E E¹ and the flange or shoulder f⁶ of the cylinder or case F and the head or cap F¹.

The blunt wedge H has a recess or shoulder h¹ to receive the head K² of the connecting rod K. The wedge is preferably of a cored out or spider construction as shown in the drawing.

The followers C slide or reciprocate upon and are supported by removable guides or plates M secured to the draft lugs or members D by bolts m.

As in my invention, the wedge or buffer block H against which the draw-bar acts through the front follower has its wedge faces arranged very blunt and acts directly upon the friction blocks or shoes G, and as the great frictional resistance between the shoes and casing is developed by reason of the extremely sharp or acute slant of the friction faces of the casing to the axis thereof, and not by reason of any increase or

multiplication of power by the wedge faces of the buffer block or wedge H, the friction shell or casing F is free from all violent bursting strains after the spring has been compressed solid by some extremely heavy shock of the draw-bar as unavoidably sometimes happens in practical use. Because after the springs have once been compressed solid and the friction shoes or blocks G thus prevented from further inward movement, the blunt wedge or buffer block H exerts and can exert but slight transverse or bursting strain upon the casing or cylinder F through the friction shoes G. This I have demonstrated by practical test and experiment, the same showing that a friction casing or shell F six and five eighths inches in diameter and five-eighths of an inch in thickness in the form of a plain cylindrical shell, and without any of the customary reinforcing circular ribs or bands to strengthen it against bursting, while resting upon a solid foundation will successfully withstand successive blows of a four and one half ton drop hammer at upward of six feet without bursting the casing, and leaving the draft rigging still in operative and serviceable condition.

I claim:—

1. In a friction draft rigging, the combination with a draw-bar, draft yoke, draft lugs, spring and followers, of a longitudinally movable friction shell having a plurality of longitudinally extending and slightly slanting internal friction faces, a plurality of longitudinally movable segmental friction shoes within said friction shell, and having each an external friction face conforming to and in sliding frictional engagement with one of said longitudinally extending and slightly slanting internal friction faces of said shell, each of said friction shoes also having at its outer end a blunt wedge face and a wedge having a plurality of blunt wedge faces, one for and engaging the blunt wedge face of each of said friction shoes, said friction shoes being provided with beveled faces at the outer portions of their inner ends and a bearing plate interposed between the inner ends of the friction shoes and the adjacent end of the spring to concentrate the pressure of the spring against the central portion of the inner ends of the shoes, substantially as specified.

2. In a friction draft rigging, the combination with a friction case having a plurality of curved internal, slightly slanting, separate and distinct longitudinal cylindrical friction faces, of a plurality of friction shoes having external curved friction faces engaging the internal friction faces of said case, and provided at their outer ends with blunt angle wedge faces, a blunt faced wedge bearing against said shoes and a spring reacting at one end against the friction shell and at the other against the friction shoes, the fric-

tion face of each of said shoes being in full contact with one of the friction faces of said shell in all positions of the shoes as they move longitudinally back and forth in the shell, substantially as specified.

3. In a friction draft rigging, the combination with a friction case having a plurality of internal slightly slanting longitudinal friction faces, of a plurality of friction shoes having external friction faces engaging the internal friction faces of said case, and provided at their outer ends with blunt angle wedge faces, a blunt faced wedge bear-

ing against said shoes and a spring reacting at one end against the friction shell and at 15 the other against the friction shoes, a bearing plate interposed between the inner ends of said friction shoes and the adjacent end of the spring, the central portions only of the inner ends of the shoes engaging said 20 bearing plate, substantially as specified.
